CARBONATOR

Carmelo V. Di Pietro, Birmingham, Mich.

Application December 31, 1945, Serial No. 638,526

6 Claims. (Cl. 261—95)

1

This invention relates to carbonators and more particularly to carbonators of the instantaneous type in which carbon dioxide gas and water are mixed to maintain a constant volume of carbonated water regardless of the rate of draft.

An object of the invention is to provide a carbonator of the type referred to featured by simplicity, ease of service and low cost.

Another object of the invention is to provide a carbonator in which the inflow of water is maintained in definite proportion to the inflow of gas so that a maximum absorption of gas by water will result.

A further object of the invention is to provide a carbonator with a header wall that serves to receive and mix water and gas and as an outlet for carbonated water.

Other objects of the invention will appear from the following description taken in connection with the drawing, which forms a part of this specification, and in which:

Fig. 1 is a vertical sectional view of a carbonator incorporating the invention.

Fig. 2 is a top plan view of the carbonator.

Fig. 3 is a diagrammatic view of the carbonator with the water and gas supply systems associated therewith.

The carbonator portion of the present invention is indicated generally by the numeral 10 and is made up of relatively few parts. A shell 11, preferably of cylindrical form, has a fixed bottom wall 12 and a top header wall 13, preferably formed of plastic or some non-conductor material, detachably fixed by bolts 14 to a ring flange 15 secured to the exterior top end of the shell. The bottom wall has a central upstanding boss 16 aligned with a depending boss 17 on the header wall and such bosses serve as pilot means for a stand pipe 18 within and substantially co-extensive with the shell 11. Such stand pipe has a sliding fit on the bosses and a sealing ring 19, located in a recess around boss 17, engages the head end portion of the pipe.

The space between the shell 11 and stand pipe 18 provides a chamber 29 for receiving a mixture of carbon dioxide gas and water and it is filled with wool 20 formed of strips of material such as stainless steel. The wool filled chamber communicates the bottom interior of the stand pipe through means of slots 21 formed in the pipe and extending above the boss 16. Such slots provide the only fluid connection between the chamber 29 and the interior of the stand pipe 18.

Carbon dioxide gas and water flow into the shell through the header wall 13 and water ab-

2

sorbed with gas flows out of the header wall through the draft tube 28, thus the water and gas mixture flows downwardly the full length of the chamber 29 in contact with the steel wool before entering the stand pipe and the draft tube. The inner bottom portion of the header wall is formed with a shallow recess 22, preferably circular and exterior of boss 17, forming a mixing chamber for carbon dioxide gas and water. A diffuser ring 23 having minute orifices 24 therethrough is fitted into the bottom of recess 22 and is suitably secured against the chamber forming wall. This diffuser ring may be formed of metal or plastic material.

Water and gas passages 25 and 26 lead through the header wall to the mixing recess 22 and their inlet ends extend through bosses 27 and 27' projecting from the peripheral surface of the header wall.

An outlet draft tube 28 extends through the header wall and boss 17 into the stand pipe. It has an open bottom end preferably located adjacent boss 16. The tube is fixed in sealed relation with the header wall and is suitably connected with a draft arm (not shown) by pipe 59.

The header wall provides inlets for water and gas, an outlet for carbonated water, a mixing recess for the water and gas and a carrier for the diffuser. Upon removal of the bolts 14, the header wall with the draft tube attached may be removed from or assembled with the shell. While the header wall is removed, the stand pipe may be readily inserted or removed from the shell, and the steel wool may be inserted or removed from the shell. This arrangement of the carbonator parts provides a structure having simplicity and accessibility for service.

A check valve, as indicated by the numeral 30, is carried in each of the bosses 27 and 27' and is formed of rubber having an inner end with a normally closed orifice 31 therein. A suitable gas conduit 32 is fixed at one end to boss 27 by coupling 33 and is fixed at its other end to a carbon dioxide drum 34, such conduit having a pressure regulating valve 35 therein. A water conduit 36 is fixed at one end by coupling 37 to boss 27' and leads from pump 38 connected by conduit 39 with a source of water 40.

The pump is preferably operated by an electric motor 41. Power line 42 leads to control device 43 and power line 44 leads to the motor, the motor being connected with the control device by line 45. The control device is connected to circuit control means responsive to water levels in the carbonator so that the motor will be automati-

cally conditioned to operate the pump to maintain a predetermined water volume in the chamber. As shown, such control means comprises two electrodes 46 and 47 both extending into the stand pipe from the header wall, the top terminals of the electrodes extending into the header wall and being engaged by screws 48 which also secure lines 49 and 50 on the wall. Such lines lead to the control device. The lower ends of the electrodes are arranged at different levels in the carbonator and such difference determines the control of the pump motor for cut in and cut out. When the water level contacts electrode 46, the circuit to the pump motor will be broken thereby cutting out motor operation and when the water level falls below the lower electrode 47 the current is completed to the motor thereby operating the pump. Obviously one electrode could be employed as the motor cut out and other suitably operated means could be provided to cut in the motor. A pressure gage and relief valve unit 50 is carried by the header wall and is in communication with the chamber in the shell through passage 25. The stand pipe 18 has a pressure relief opening 51 above the water level. A suitable chamber may be formed around the shell by an outer shell 60 for the reception of refrigerating means such as ice or a mechanical system (not shown).

What I claim is:

1. A carbonator comprising a shell, a bottom wall closing one end of the shell, a stand pipe coextensive with the shell and spaced interiorly thereof to form a chamber, said stand pipe having its bottom end in communication with the bottom portion of the chamber, steel wool substantially filling the chamber, a header wall detachably fixed on the upper end of the shell, a boss depending from the header wall on which the upper end of the stand pipe is piloted, a draft tube in the stand pipe fixed to the header wall, said header wall having a shallow recess in the bottom portion forming a mixing chamber and water and carbon dioxide gas passages therein leading to such space, and a diffuser in the header wall at the bottom of the recess.

2. A carbonator comprising a shell, a bottom wall closing one end of the shell and having an upstanding pilot boss, a stand pipe in the shell piloted on the boss, said stand pipe being spaced from the shell forming an intermediate chamber and having openings therethrough above the boss, steel wool substantially filling the chamber, a header wall detachably fixed on the upper end of the shell having means for closing the upper end of the stand pipe, a draft tube fixed to the header wall and extending into the stand pipe, said header wall having a bottom shallow recess above the chamber and passages for water and carbon dioxide gas leading to the recess, and a diffuser fixed in the header wall at the bottom of the recess.

3. A carbonator comprising a shell, a bottom wall closing one end of the shell and having an upstanding pilot boss, a stand pipe coextensive with the shell and spaced interiorly thereof to form a chamber, said stand pipe having its lower end slidably piloted on the boss and slotted above the boss, steel wool substantially filling the chamber, a header wall detachably fixed on the upper end of the shell, a pilot boss depending from the header wall and slidably arranged in the upper end of the stand pipe, a draft tube in the stand pipe fixed to the header wall, said header wall having a shallow recess in the bottom portion forming a mixing space overlying the chamber and formed with passages for receiving water and carbon dioxide gas leading to said space, and a diffuser fixed in the header wall at the bottom of the recess.

4. A carbonator comprising a shell, a bottom wall closing one end of the shell, a stand pipe coextensive with the shell and spaced interiorly thereof to form a chamber, said stand pipe having its bottom portion in communication with the bottom portion of the chamber, steel wool substantially filling the chamber, a header wall detachably secured on the top end of the shell, a draft tube in the stand pipe fixed to the header wall, water inflow control means in the stand pipe fixed to the header wall, said header wall having a recess in the bottom portion forming a mixing space overlying the chamber and water and carbon dioxide gas inlet passages therein leading to the recess, and a diffuser fixed in the header wall at the bottom of the recess.

5. A carbonator comprising a shell closed at the bottom end and open at the top end, a header wall detachably fixed over the top end of the shell, a draft tube carried by the header wall having its intake end adjacent the bottom of the shell, said header wall having a circular shallow recess open to the interior of the shell and inlet passages for water and carbon dioxide gas leading to the upper portion of the recess, and a diffuser ring fixed to the header wall in the bottom of the recess, said ring having a plurality of minute orifices therethrough opening to the interior of the shell.

6. A carbonator comprising a shell closed at the bottom and open at the top, a header wall detachably fixed over the top of the shell, a boss depending from the bottom of the header wall, a stand pipe telescoping the boss and open to the interior bottom portion of the shell, a draft tube in the stand pipe fixed to the header wall, said wall having a circular recess in the bottom portion thereof surrounding the boss and water and carbon dioxide gas inlet passages leading to the recess, and a diffuser ring fixed to the wall in the bottom of the recess.

CARMELO V. DI PIETRO.
